[57] CLAIM

The ornamental design for a belt mounted holder for golf tees, rifle caps, or similar article, substantially as shown and described.

DESCRIPTION

FIG. 1 is a front elevational view of a belt mounted holder for golf tees, rifle caps, or similar article showing my new design, the rear view being identical thereof; FIG. 2 is a top plan view thereof, the bottom view being identical thereof;

FIG. 3 is a left end elevational view thereof; and

FIG. 4 is a right end elevational view thereof.

Fig. 1.
